UNITED STATES PATENT OFFICE.

ORLAND D. ORVIS, OF CHICAGO, ILLINOIS.

HYDROCARBON-FURNACE.

SPECIFICATION forming part of Letters Patent No. 313,101, dated March 3, 1885.

Application filed January 16, 1884. (No model.)

To all whom it may concern:

Be it known that I, ORLAND D. ORVIS, a citizen of the United States, residing in Chicago, county of Cook, and State of Illinois, have invented certain new and useful Improvements in Hydrocarbon-Furnaces, of which the following is a specification.

This invention relates to improvements in hydrocarbon-furnaces, for which Letters Patent of the United States, No. 288,477, were granted me November 13, 1883, and is designed to be used in connection with fire-chambers in which there is an unusually strong draft—as, for instance, railroad and fire engines, &c.

15 The objects of this invention are to avoid any possibility, by reason of an unusually strong draft, of the hydrocarbons escaping into the fire-chamber in a liquid form, to more effectually commingle both the vaporous and liquid 20 hydrocarbons with the steam and air during their admission to the retort, in which they afterwards rise and escape only in a vaporous condition into the fire-chamber.

Further objects of my invention are to prevent 25 the escape of liquid hydrocarbons into the injector, and thereby avoid any possibility of their dripping into or through the air-supply pipe of the injector, and also to simplify the connection of the injector with the retort.

30 I attain these objects by devices illustrated in the accompanying drawings, in which—

Figure 1 is a longitudinal section in detail of devices embodying my invention; Fig. 2, an enlarged perspective view of the nipple connecting the injector and retort, and having formed therewith a drip-cup and deflector.

Similar letters of reference indicate the same parts in both figures of the drawings.

A represents a detail section of a water-jacket fire-chamber—such as is employed in railroad and other engines—and B an injector consisting of a globe vacuum-chamber, a, an air-supply pipe, b, a curved steam-jet, c, and an oil-supply nozzle, d, projected through the neck or tapping of the injector at a right angle to and just above and in front of the steam-jet. Inside of the fire-chamber is a retort, C, provided near its upper end and on its inner side with an opening, preferably elongated 45 horizontally, and forming an inlet for the es-

cape of hydrocarbon vapors to the fire-chamber.

The injector and retort are substantially the same in construction as set forth in the patent referred to; but it should be understood that 55 my present invention is not limited to these special constructions, and may be applied to others varying materially in their form and arrangement.

Passing through the wall of the fire-chamber is a nipple, D, screw-threaded on its projecting ends, for the direct attachment thereto of both the injector and the retort, and forming the supply-passage of the hydrocarbon, air, and steam to the retort from the injector. Depending from the upper portion of the nipple is a deflector, E, formed continuous with the nipple, and projecting downwardly at an oblique angle to the length of the nipple, said deflector being preferably formed by cutting 70 away a portion of the nipple, leaving enough to form the deflector, which is then bent downwardly, as shown; but the deflector may consist of a separate piece joined to the nipple or to the retort in any suitable manner. By 75 the employment of this deflector it will be seen that the liquid portions of the hydrocarbons passing through the nipple to the retort are not only thrown downwardly to the bottom of the retort, but striking against 80 the deflector are broken up, and hence more thoroughly commingled with the inflowing steam and air, and also the steam and air more effectually commingled with each other before entering the retort than if the deflector were 85 omitted. The ultimate object of this, and also the invention set forth in my patent, is to introduce into a fire-chamber hydrocarbons only in a vaporous form, and in furnaces of medium draft this object is attained without the 90 employment of a deflector; but by experiment it is found that in fire-chambers—such, for example, as those of railroad-engines, where the steam-power is very high—liquid portions of the hydrocarbons are forced through the retort into the fire-chamber, and result in smoke and a proportionate waste of the hydrocarbons.

By the employment in this class of fire-chambers of the deflector these objections are entirely avoided, for not only are the hydrocar- 100

bons, steam, and air more thoroughly com-
mingled, but are thrown down into the retort,
and of necessity rising before escaping to the
fire-chamber, the hydrocarbons are not only va-
porized in the heated retort, but these vapors
are raised to a high temperature and expanded
before they escape, the expansion serving to
cause them to enter the furnace with great
force, which is very desirable, for they are
correspondingly spread over a greater portion
of the fire-chamber. Preferably the deflector
is projected below the plane of the retort-out-
let, as shown, and for the reason that it may
afford a surface against which the impinging
of the expanded vapors will cause them to re-
act and be thrown with greater force into the
furnace. In other words, that portion of the
retort above the free end of the deflector is
converted into an expansion-chamber, from
which the vapors can only escape into the fire-
chamber, their accumulated force in the ex-
pansion-chamber depending upon the force of
the steam and air and the relative dimensions
of the ingress and egress openings of the retort.
To prevent the escape of the liquid hydro-
carbons from the nipple into the air-supply
pipe, a projection, F, is formed upon the un-
der side of the nipple, in the same manner as
the deflector; but instead of being bent down
at its juncture with the nipple it has only its
free end slightly turned up to form a drip-cup,
which will not interfere with the passage of
air between it and the steam-nozzle; but this

drip-cup may be formed by a plate projecting
from the edge of the globe vacuum-chamber 35
at the juncture therewith of its tapping.

The advantages of forming the deflector and
drip-cup with the nipple are that it requires
but little labor and expense and facilitates and
simplifies the connection of the retort and in- 40
jector.

Having described my invention, what I
claim, and desire to secure by Letters Patent,
is—

1. The combination, with the retort and the 45
supply-passage thereto, of a deflector project-
ing downwardly into the retort from the up-
per edge of said passage, substantially as de-
scribed.

2. The combination, with the supply-pas- 50
sage and the deflector projecting downwardly
from the upper portion of said passage, of a
retort provided with an outlet, and with an
expansion-chamber extending below said out-
let, and between the outlet and the opening of 55
the supply-passage into the retort, substan-
tially as described.

3. The combination, with the injector, the
oil-supply nozzle, and the passage D, of the
air-pipe and a drip-cup, formed, substantially 60
as described, below the oil-nozzle, as and for
the purpose set forth.

ORLAND D. ORVIS.
